UNITED STATES PATENT OFFICE.

THOMAS GROVES, OF ST. LOUIS, MISSOURI.

AUTOMOBILE SIGNAL.

Application filed August 13, 1919. Serial No. 317,321.

To all whom it may concern:

Be it known that I, THOMAS GROVES, a citizen of the United States, residing in the city of St. Louis and State of Missouri, have invented new and useful Improvements in Automobile Signals, of which the following is a specification, reference being had to the accompanying drawings.

This invention pertains to automobile signals, and the prime object of the invention is to produce a simple and practical device for this purpose, the working parts whereof are operable preferably by electricity, and which may be readily attached to, or adjusted upon the front or rear portions of an automobile, and so that the indicating member thereof may be readily controlled by the hand of the operator, for the purpose of indicating to pedestrians and others the direction that the vehicle is to pursue.

A further object is to provide a simple and efficient electrical means for operating the working elements of the device, including the signaling semaphore.

A further object is to produce a practical device for the purpose intended to meet the requirements of a commercial article of this kind.

With these and other objects in view, attention is called to the accompanying drawings, wherein—

Fig. 1 shows a longitudinal elevation of the device detached from the vehicle, a central section of the casing being broken away to reveal the inner parts;

Fig. 2, a top plan view of the device;

Fig. 3, a diagrammatic view showing the lay-out of the several working elements of the device;

Fig. 4, a plan view showing the arrangement of the electromagnets and armature.

Referring more particularly to the drawings, my invention consists of a combination of a suitable switch or control box mounted upon the dash or instrument board of the automobile, and which carries suitable electrically operated control elements for the manipulation of the signal per se, the subject of this present application. This switch box is not indicated in the drawings for the reason that it will be made the subject of a separate application for patent.

In carrying out the present invention, a box or casing 3 is mounted either at the front or rear of the machine, or both at the front and at the rear. Through the casing

3, at the points 10 and 11, is vertically journaled the shaft 9. At the point where the shaft 9 emerges through the top 12 of the casing 3, a sleeve 13 freely encloses the shaft 9, which shaft extends upwardly through the top 12 of the casing.

The semaphore 14—15 as a whole represents an arrow. It is made up of two sections, the arrow-head section 14, which is rigidly and horizontally mounted from its rear end directly to the upper end of the shaft 9 and rotates therewith, and the tail section 15 mounted in alignment with the section 14, the lower edge being bracketed from the sleeve 13 by means of the rigidly attached bracket 16, and the upper edge being pivoted in vertical alignment with the shaft 9 by means of the rigidly attached bracket 17, same having pivotal connection at 18 with the upper edge of the forward section 14. Thus the two sections 14 and 15, while pivoted in alignment one to the other, may be rotated or oscillated sidewise independently of one another. An upper retractile coil spring 24 connects the sleeve 13 with the wall of the casing 3 between the points 20 and 21, while a similar spring 19 connects the shaft 9 with the wall of the casing between the points 22 and 23. The action of these springs is normally to hold the semaphore 14—15 in a straightaway forward position, and so that the magnet 8 would stand transversely positioned between the magnets 6 and 7.

The sleeve 13 is adapted to be locked in relation to the shaft 9 by means of an ordinary clutch mechanism, consisting of the sliding clutch 25 mounted upon the shaft 9 immediately below the sleeve 13, same having upper clutch teeth 26 adapted to engage the complementary clutch teeth 27 at the lower end of the sleeve 13. A key 28 guards the clutch 25 against rotating on the shaft 9, while the same is adapted for longitudinal movement thereupon. The clutch 25 has an annular guide-way 29 adapted to receive the prongs 30 of the clutch lever 31. The clutch lever 31 is pivoted to the casing at the point 32. The outer end 33 of the clutch lever 31 extends over the upper end of the electro clutch magnet 34, the said end 33 acting as an armature in relation to said magnet 34. Thus as the end 33 is oscillated thru the action of said electro clutch magnet 34, the clutch 25 is thrown into or out of engagement with the

sleeve 13, thus locking the sleeve relative to the shaft 9.

Any suitable electro-magnetically operated mechanism may be mounted within the casing 3 to control the signal elements, and wiring extended, of course, to a battery and to the control box on the dash to actuate the electro-magnetic apparatus.

The semaphore as a whole normally 10 points straight ahead, and four signals are indicated by this device; a turn to the right by turning the arrow-head to the right; a turn to the left, by turning the arrow-head to the left; a stop signal by turning the 15 semaphore to point to the right; and a back up signal by turning the entire semaphore to point to the left.

While I have herein described a certain 20 specific manner and method of constructing and assembling the elements of my invention, it is understood that I may vary from the same in minor details, not departing from the spirit of my invention, so as best to construct a practical device for the purpose 25 intended, as defined in the appended claims.

What I claim to be new and patentable is:

1. In an automobile signal, a casing to 30 carry the signal elements; a shaft journaled vertically through the center of the casing and extended upwardly; a sleeve journaled in the top of the casing around the base of the shaft; an arrow head horizontally

joined to the end of the shaft; an arrow tail similarly joined to the sleeve; and springs for normally holding the arrow head and 35 tail in alignment.

2. In an automobile signal, a casing; a shaft journaled vertically through the center of the casing and extended upwardly; a sleeve journaled in the top of the casing 40 around the lower part of the protruding shaft; an arrow head horizontally joined to the protruding end of the shaft; an arrow tail similarly joined to the sleeve; springs for normally holding the head and tail in 45 alignment; and means for rotating the head and tail independently or in unison, as desired.

3. In an automobile signal, a casing; a 50 shaft journaled vertically through the center of the casing and extended upwardly; a sleeve journaled in the top of the casing around the lower part of the protruding shaft; an arrow head horizontally joined to the protruding end of the shaft; an arrow 55 tail similarly joined to the sleeve; springs for normally holding the head and tail in alignment; and electro-magnetic means for rotating the head and tail independently or in unison, as desired.

THOMAS GROVES.
